UNITED STATES PATENT OFFICE.

CHARLES M. SIMPSON, OF HOUSTON, TEXAS, ASSIGNOR OF FIVE-SIXTHS TO HOWARD F. SMITH, OF HOUSTON, TEXAS.

TRACK-LAYING MACHINE.

1,124,343.

Specification of Letters Patent. Patented Jan. 12, 1915.

Application filed April 17, 1914. Serial No. 332,537.

To all whom it may concern:

Be it known that I, CHARLES M. SIMPSON, a citizen of the United States, residing at Houston, in the county of Harris and State 5 of Texas, have invented certain new and useful Improvements in Track-Laying Machines, of which the following is a specification.

This invention relates to new and useful 10 improvements in track laying machines.

The object of the invention is to provide a delivering mechanism to be used in connection with a track laying machine heretofore invented by me and disclosed in Letters Patent 15 of the United States issued to me by the United States Patent Office on May 27, 1913, the number of said patent being 1,062,743; and embodies a construction whereby railway ties may be delivered upon the road 20 bed, from the cars on which they are hauled, in position to receive the rails.

A further feature of the invention resides in the provision of a means for adjusting the delivering mechanism to accommodate it to 25 the direction of the road bed, so that the ties may be delivered at the exact place which they are to occupy in the track, as in the case of curves or bends, or other irregularities in the course of the road bed.

With the above and other objects in view, the invention has particular relation to certain novel features of construction, operation and arrangement of parts, an example 35 of which is given in this specification and illustrated in the accompanying drawings, wherein—

Figure 1 is a plan view of the delivering mechanism attached to the front end of a track laying machine. Fig. 2 is a sectional side elevation thereof, shown in its relation 40 to the railway track. Fig. 3 is a fragmentary plan view of a delivery track. Fig. 4 is a fragmentary side elevation thereof. Figs. 5 and 6 show detail views of the delivery track adjusting mechanism. Fig. 7 shows a fragmentary view of the stirrup which supports the delivery track. Figs. 8 and 9, respectively, show plan and edge views of the support to which the inner end 45 of the delivery track is pivoted, and Fig. 10 shows a fragmentary view of the tie deflector.

Referring now more particularly to the drawings, the numerals 1 and 2 refer, respectively, to the side members of the frame

work of the machine and the numeral 3 refers to the front cross beam, which is fixed at its respective ends to said side members. The side members project forwardly beyond said cross beam, as shown in Figs. 1 and 2. 60

A delivery track is provided formed of the end members 4 and 5 and the side members 6 and 7. The inner end of the delivery track is pivoted to the support 8, which is secured at the center of the cross beam 3 65 underneath and projects forwardly therefrom. This track declines forwardly, as shown in Fig. 2, so that when the ties are delivered thereon they will pass down over the track by force of gravity and be delivered on to the road bed. A stirrup 9 is provided whose respective ends are secured to the front ends of the side members 1 and 2 and which depends from said side members. The delivery track extends through 70 this stirrup and its forward end is supported thereby. Each of the side members 6 and 7, of the delivery track, is formed of lengthwise extending beams, 6^a, 6^a and 7^a, 7^a and between them are mounted rollers 10 supported on suitable axles 11 whose ends have bearings in said beams 6^a and 7^a. The rollers of each side members 6 and 7 are arranged in staggered relation, so as to bring them closer together and the rollers project 75 above the beams 6^a and 7^a so as to facilitate movement of the ties along the track. 80

The stirrup 9 is considerably wider than the delivery track so as to permit said track to have a certain amount of lateral movement in the stirrup. This lateral movement is necessary in order to keep the delivery end of the track alined over the road bed in going around curves and the like, as is indicated in dotted lines in Fig. 1. For the 85 purpose of adjusting the delivery track laterally, I have provided the link 12, the inner end of which is pivoted to one side of said track and the outer end of which is pivoted to the inner end of the extended hub 13 of 100 the hand wheel 14. This hub is outwardly threaded and engages in an inwardly threaded transverse hole extending through the side member 2. It is obvious that by turning the hand wheel 14, the delivery 105 track may be adjusted to one side or the other, as desired. The ties pass endwise along the tramway 16, moving over the rollers 17 thereof and the front end of the tramway is inwardly curved so that the ties will 110

leave it in a diagonal position relative to the framework and road bed and when in this position the rear end of the tie will be supported by the roller 17 located on the inner side of the front end of the tramway. The front end of each tie strikes against the deflector 18 and is deflected transversely of the delivery track. This deflector is supported by the side members 1 and 2, and is preferably formed of an upstanding flange, formed, substantially in a curve, as shown. The tie is delivered with considerable velocity against said deflector and its forward end passes around the deflector until it strikes against the stop 19. This stop is placed so that the forward end of the tie will strike it just as the rear end leaves the tramway 16 and the tie will then drop down on to the delivery track in a transverse position and as the framework 18' is elevated a considerable distance above said track, the tie will pass along the track under said framework and will be delivered by gravity from the track onto the road bed in a transverse position.

What I claim is:—

1. A device of the character described including a suitable frame work, a delivery track, one end of which is pivoted to the front end of the frame work and which declines therefrom, a stirrup depending from the framework and through which said track extends and by means of which the free end thereof is supported and means for adjusting the track laterally in said stirrup.

2. A device of the character described including a suitable frame work, a tie tramway carried thereby, a delivery track, one end of which is pivoted to the front end of the framework and which declines forwardly therefrom, a transverse deflector arranged above said track and alined with the front end of the tramway, a stirrup depending from the framework through which said track extends and by means of which the free end thereof is supported and means for adjusting the front end of said track laterally in the stirrup.

3. A device of the character described including a suitable framework, a tie tramway carried by one side thereof, a delivery track, one end of which is pivoted to the front of the framework and which declines forwardly therefrom, said track being formed of two side members, suitably secured together, and antifriction rollers carried by said side members, a transverse deflector

carried by the framework and arranged above said track and in front of said tramway, a means for supporting the free end 60 of said track and a means for adjusting said free end laterally, relative to the framework.

4. A device of the character described including a suitable framework, a delivery track attached thereto and declining forwardly therefrom, said track being composed of side members fixed in their position relative to each other, each side member having a plurality of antifriction rollers extending above its upper surface, said rollers being 70 arranged in staggered relation to one another.

5. A device of the character described including a suitable frame work, a delivery track, one end of which is pivoted to the 75 front end of the framework, and which declines forwardly therefrom, said track including two side members fixed in their relation to each other and antifriction rollers carried by the side members and projecting 80 above the upper surface thereof, a stirrup depending from the framework and through which said track extends and by means of which the free end thereof is supported and means for adjusting the track laterally in 85 said stirrup.

6. A device of the character described including a framework, a tie tramway arranged along one side thereof, a delivery track pivoted at its rear end to the front 90 end of the framework, said delivery track declining forwardly and a transverse deflector supported by the framework, arranged in front of the tramway and spaced above the rear end of said delivery track. 95

7. A device of the character described including a framework, a tie tramway arranged along one side thereof and having its forward end inwardly curved, a transverse deflector supported by the framework 100 and spaced a distance in front of the delivery end of the tramway, a delivery track, whose rear end is pivoted to the front end of the framework underneath said deflector, said track declining forwardly and means 105 for adjusting the free end of said track laterally.

In testimony whereof I have signed my name to this specification in the presence of two subscribing witnesses.

CHARLES M. SIMPSON.
